UNITED STATES PATENT OFFICE.

JOHN AGELL, OF NEW YORK, N. Y., ASSIGNOR TO ALLADIN TOY COMPANY, INC., OF NEW YORK, N. Y., A CORPORATION OF NEW YORK.

DESIGN FOR A TOY HORSE.

Application filed June 30, 1924. Serial No. 10,006. Term of patent 14 years.

To all whom it may concern:

Be it known that I, JOHN AGELL, a citizen of the United States, residing at 125 West 64th Street, city of New York, in the county of New York and State of New York, have invented a new, original, and ornamental Design for Toy Horses, of which the following is a specification, reference being

had to the accompanying drawing, forming part thereof.

The figure is a perspective view of a toy horse showing my new design.

I claim:

The ornamental design of a toy horse, as shown.

JOHN AGELL.
